(57) **CLAIM**

The ornamental design for a display screen with icon group and display screen with icon set, as shown and described.

DESCRIPTION

FIG. 1 is a front view of a display screen with icon group showing our new design; and,

FIG. 2 is a front view of a display screen with icon set showing our new design.

The broken line showing of the display screen is for the purpose of illustrating environment and forms no part of the claimed design.
